UNITED STATES PATENT OFFICE

2,450,985

POWER SUPPLY FOR ELECTRONIC APPARATUS

Lawrence R. Paust, Chicago, Ill.

Application August 30, 1945, Serial No. 613,599

12 Claims. (Cl. 315—95)

1 This invention relates to a power supply for electronic apparatus, and more particularly to means for energizing electronic tubes from an alternating current power source.

One feature of this invention is that it provides suitable filament and plate supplies for electronic tubes with power of any amount desired; i. e., the plate voltages can be several times the voltage of the A. C. supply source, with attendant maximum power output of the tubes.

Another feature of this invention is that it effects the desired power supplies to the tubes by use of a transformer designed to handle only the plate power requirements of the amplifying tubes, with the cathode heating connections of such tubes being connected directly to the A. C. supply source, rather than through a transformer. This enables a very much smaller power transformer to be used, particularly important in small and close packed electronic apparatus, as the smaller transformer requires less space and has much smaller magnetic and electrostatic fields. Such a transformer, moreover, has a cost only a small fraction of that of the normal power supply transformer.

Still another feature of the above-described method of providing filament and plate supplies for electronic tubes is that the chassis and the B— return lead are isolated from the commercial power supply circuit, "floating" as it is sometimes termed. This is particularly important where units are to be connected to other units powered from a different wall socket, for example, since heretofore full transformer power supply systems have been the only way to avoid large circulating currents in the chassis and the necessity of isolating connections between the units.

A further feature of this invention is a new and improved method of energizing a pilot lamp. Heretofore pilot lamps have usually been operated from a filament winding on the power transformer in A. C. sets or connected in series with the filaments in A. C.-D. C. sets, or in parallel with a resistance in series with the filaments, and in both these latter cases the pilot lamp has been very greatly over-energized when the set was first turned on. Another method of energizing a pilot lamp required a tube with a center tapped filament, not very satisfactory in practice. I am here disclosing a system of energizing a pilot lamp as a function of the plate supply current, either alone or also as a function of the filament supply current, and so arranging matters that the pilot lamp is never over-energized or caused to "flash up" with undue brilliance.

2 Other features and advantages of this invention will be apparent from the following specification and the drawings, in which:

Figure 1 is a partial schematic diagram of one system embodying my invention; an intercommunicating system in the particular case illustrated; Figure 2 is a circuit diagram of one of the intercommunicating units shown in Figure 1, as the uppermost unit of such figure; Figure 3 is a circuit diagram of a portion of the power supply circuit showing a different pilot lamp energizing arrangement; Figure 4 is a circuit diagram of a portion of the power supply showing still another pilot lamp energizing arrangement; and Figure 5 is a circuit diagram similar to Figure 3 in so far as the pilot lamp energizing circuit is concerned but showing a full wave rectifying arrangement.

The power supply arrangement which I am here disclosing and claiming, both in those aspects which relate to energizing the electronic tubes and in those aspects which relate to energizing a pilot lamp, is useful in any type of electronic apparatus, as radios, public address systems, paging systems, electronic controls, etc. merely to name a few representative examples, but I am here illustrating it in connection with an intercommunicating system. It will be understood, however, that no limitations are to be construed from the specific system in which I illustrate it and in which I will now describe my invention.

Referring first more particularly to Figure 1, electronic apparatus incorporating my improvements is illustrated as an intercommunicating system comprising three master units 10, 11 and 12, it being understood that there would normally be a larger number of master units and generally certain subordinate units (comprising only speakers and switches and generally called substations) associated with each master unit. Each of the units shown is connected by its local or branch cable to a master cable or interconnecting system here identified as 13. Associated with the intercommunicating units is a general communicating system shown as comprising an amplifier 14 adapted to energize speakers 15a and 15b and another amplifier 16 adapted to energize speakers 17a—d.

Each of the units 10, 11 and 12 comprises, in the particular case illustrated, a dynamic speaker adapted to be operated selectively by a talk-listen switch having its control means identified as 10a, 11a and 12a, so that it performs its speaker function when communication is being received and performs the function of a microphone when

communication is going out from any particular unit; an amplifier generally comprising 2 or 3 amplifying tubes in cascade; a power supply, as will be hereinafter more fully described; a switching arrangement for selecting the other unit or units of the system with which communication is desired, and any other desired additional controls, as the volume controls here identified as 10b, 11b and 12b and, in the case of the units 11 and 12, paging switches 11c and 12c. The controls 10b, 11b and 12b are adapted to provide on-off switch operation for the units, and manual volume control; and the controls 11c and 12c enable the units having such controls to actuate the general communicating system.

Inasmuch as the details of this particular intercommunicating system which I have chosen to illustrate as one place where my invention here being claimed may be embodied has been fully described and claimed in my Patent 2,366,552 of January 2, 1945, it is felt that further detail description of the general apparatus is unnecessary, and I will now direct my description to the circuit diagram comprising Figure 2.

This figure shows a circuit diagram for one of the master units illustrated in Figure 1, as the unit 10, without a paging control. The dynamic speaker 20 is shown as adapted to have its actuating or voice coil connected to the primary of transformer 21, in the position of the switch 22 as shown in solid lines in the drawing, or to the wire 23 in the position of the switch as shown in dotted lines. The first mentioned position of the switch causes the translating device 20 to operate as a microphone, with current variations generated thereby being delivered through an appropriate input network including the transformer 21 to the first amplifying tube 24 which tube may be of tube type No. 12SJ7, as a representative example. The amplified output of this tube 24 is here shown as delivered through an appropriate resistance coupling arrangement to the second amplifying tube 25, which may be of tube type No. 35L6, as a representative example. The output of this tube is delivered through an output arrangement including the transformer 26, the switch 27, and the selector switch 28 to the cable connection. The switches 22 and 27 are ganged for operation by the control 10a, the switches being in the position shown in solid lines when the control 10a is as illustrated in Figure 1, with the operator of unit 10 talking; and the switches are moved to the dotted line position by appropriate control operation when the operator of unit 10 desires to listen. Operation of the selector switch 28 enables interconnection of unit 10 with either of the units 11 or 12, for example, to effect communicating connections with the translating devices 11d and 12d thereof. Again it is felt that it would unduly burden the present specification to follow the circuits of this portion of the unit through in detail and to specify resistor and condenser values, etc., as a unit of this type has been fully described in my above-mentioned Patent 2,366,552, to which reference may be made to supplement the present disclosure. Accordingly, this specification will hereafter be concerned only with power supply arrangements for such units, these power supply arrangements including my invention with respect to tube and pilot lamp energization.

Referring now more particularly to the lower half of the sheet comprising Figure 2, connections are suitably made to a conventional source of commercial alternating current, as for example

of 110 volts, 60 cycles, through the wires 30 and 31. This circuit may be controlled by an on-off switch of the snap type here identified as 32, this switch being part of the means actuated by the control 10b of the unit 10. An A. C. ground connection is made to this side of the supply line by a condenser 33, which may for example be of .1 microfarad capacity. This "ground" connection is a connection to the chassis of the unit and to B-, in the particular case illustrated, although it will be understood that this connection may be to B- alone if desired. The power supply circuit is connected to the primary 34a of a power transformer 34, the lead 31 being connected directly to one end of this primary through the on-off switch 32 and the lead 30 being connected to the other side of the primary through a resistor 35 comprising part of the system for energizing the pilot light 36, the other portion of the means for developing pilot light energizing voltages comprising the resistor 37.

The transformer 34 is of the step-up type, with its secondary 34b preferably having at least 2 and preferably 3 to 4 times the number of turns of the primary. This transformer is here shown as having one end of its secondary grounded (to the chassis or to B-, or both) and its other end connected to the anode of a half-wave rectifying tube 38, which may be of tube type No. 35Z5. Output of this rectifying arrangement is filtered by a filter section here shown as comprising a choke 39, which may be of 5 henries inductance, and condensers 40 and 41, which may be of 20 microfarad capacity, the negative side of the arrangement being connected to ground; and the positive potential, of at least 250 volts and preferably of the order of 350 volts, is delivered through the lead 42 to the plate supply connections for the amplifying tubes 24 and 25.

Heating current for the rectifier and amplifying tube cathodes is supplied by a direct connection to the A. C. supply source, the word "direct" being used throughout this specification and claims in the sense that there is no transformer in the connection isolating the heating connections of the tubes from the supply source. Moreover, while the particular tube types mentioned and illustrated are of the type having cathode sleeves with heaters therewithin having the heating connections made thereto, this invention is equally applicable to tubes of the type where the cathode is a hot filament with the heating connections made directly thereto, as for example an amplifying tube of type No. 46 or a rectifier of tube type No. 80, so that when it is said herein that the tubes have cathodes and heating connections therefor it will be understood that this refers to either arrangement. Moreover, when the word "cathode" is used alone, it will be understood that any electron emitting element is meant, including even the cold cathode of a rectifying tube of type No. 1B48, for example.

In the particular circuit shown and being described the tubes are of the type having cathode sleeves and heaters 24a and 25a of the amplifying tubes 24 and 25 are here shown as connected in series with each other and in series with the heater 38a of the rectifying tube 38. Connection from one end of this group of three heaters in series is made through the resistor 43 and the resistors 37 and 35 to the A. C. line 30; and connection from the other end of this series circuit of the three heaters is made through the wire 44 and the snap switch 32 to the other A. C. lead 31. The value of the resistor 43 would be

selected in accordance with the proper current for the heaters; and would have a value of 300 ohms in connection with the particular hook-up here being described. It will also be understood that while the tubes are all shown as of a type having heaters carrying the same current, other tubes with greater or lesser heater draw can be used if a series parallel arrangement of the circuit is used.

With the arrangement just described it will be noted that there are no filament windings on the secondary of the transformer 34, and accordingly I use a transformer designed only to handle the plate current draw of the two amplifying tubes and of insufficient capacity to also handle filament power requirements. In the particular case illustrated the transformer need only be made large enough to handle about 15 watts, as the plate current draw will only be in the order of 60 milliamperes for the amplifying section. This enables a very small and compact transformer to be designed, with a relatively small diameter coil and a correspondingly small hole through the core, with a light core because of the small wattage involved. Filament windings are usually of quite heavy wire and of about two layers each, so that two filament windings on a secondary of a transformer substantially increase the total diameter of the windings; and cathode draw generally results in doubling the required wattage of the transformer, so that not only is the larger hole in the core needed, but also a very much heavier core. By the use of the system I am disclosing, all of the many disadvantages of a voltage doubling arrangement can be avoided, the chassis ground can be "floated," and full power potential of the amplifying tubes can be made use of by putting 250 volts or more on their plates; yet a very small and light transformer can be used, with its attendant advantages.

Ordinarily, in A. C.-D. C. sets, a pilot light is actuated as a function of the filament current flow only, resulting in the light flashing up to undue brilliance due to over voltage when the switch is first turned on; and this results in much shorter life of the pilot lights. I have found that a very satisfactory pilot light energization can be effected by the arrangement shown, resulting in the pilot light coming on at proper voltage (without over-energization) immediately upon turning the set on, and yet subsequently maintaining proper brilliance during normal operation of the apparatus when the tubes have warmed up. I effect this by making energization of the pilot light a function, although not necessarily exclusively, of plate current draw.

In the particular arrangement illustrated in Figure 2, it will be seen that the plate current draw of the amplifying tubes 24 and 25 delivered by the rectifying arrangement constitutes a current drain which must be supplied by current passing through the resistor 35 and the transformer primary 34a. Accordingly, once the amplifying tubes have heated up and space current has started to flow therethrough there will be a voltage drop across the resistor 35 which is a function of this space current and of the value of this resistor. The filament or heater draw, however, also flows through the resistor 35, the circuit in this case being through the resistor 35, the resistor 37, the resistor 43, and the heaters 38a, 25a and 24a in series, the heater 24a being last in series in order to minimize hum. Inasmuch as the pilot light 36 is connected across both resistors 35 and 37, its energization will be a func-

tion of the voltage drop across both these resistors. When the switch 32 is first turned to on position there will, of course, be no space current flow through the amplifying tubes 24 and 25, and accordingly no drop across the resistor 35 as a function of this particular power drain. On the other hand, the heater current draw is initially high, the heaters being cold, and there will be a higher than normal heater current flow through resistors 35 and 37. It is necessary, therefore, so to proportion the ratios between the resistors 35 and 37, and their total resistance, that the current drain across the resistors 35 and 37 when the switch is first turned on is just proper for the energization of the pilot light used. Under these circumstances there will be no over-voltage energization of the pilot light when the switch is first turned on. As the heaters come up to temperature the heater current draw will begin to drop, and there may be a period of a few seconds where the pilot light dims very slightly. However, in a matter of seconds the cathodes of the amplifying tubes 24 and 25 are heated sufficiently to cause space current to flow through these tubes and through the rectifying tube 38 supplying it, so that the voltage drop across the resistor 35 increases, this now being a function both of the plate current draw and of the heater current draw. This results in bringing the energization of the pilot light 36 back to proper brilliance but again without over energization and keeps the pilot light operating at the desired energization level thereafter at the normal operation of the apparatus. In the particular circuit shown and with the particular tubes mentioned, the resistor 35 may have a value of 6 ohms and the resistor 37 a value of 50 ohms for proper energization of a 6-8 volt .15 ampere pilot light. In any event, the value of the resistor 37 should always be at least several times that of the resistor 35, as the voltage drop generated in the resistor 35 by the space current draw of the amplifying tubes should only be such as to replace the drop of heater current after the heaters warm up.

Figure 3 shows a modified form of pilot light energizing arrangement wherein the A. C. power lines 50 and 51 again energize the primary of a step-up transformer 52 having one side of its secondary grounded and the other side connected to the anode of a rectifying tube 53 adapted to supply space current or plate current to the amplifying tubes of the apparatus. The pilot light 54 is in this case connected across a pair of resistors 55 and 56 in series in the circuit of the primary of the transformer, the mid point between these resistors being connected to a resistor 57 in series with the heaters of the rectifier and amplifying tubes. This alternative circuit is particularly desirable when amplifying tubes are used having such characteristics that the plate current drain is low, resulting in low primary current as a function of the plate current draw. Under these conditions the provision of the additional resistor 56 increases the effect of the plate current drain as an energizing factor for the pilot light 54. In this particular circuit all of the resistance formerly divided between the resistors 35 and 37 is concentrated in the resistor 55 which may for example have a value of about 50 ohms with the tubes heretofore mentioned; and the resistor 57 takes the place of the resistor 43 in my first modification, and might have a value of 300 ohms. The original heater current draw thus results in the same initial voltage drop

across the resistor 55 as was the case of the initial drop across the resistors 35 and 37 in my first form; and this is all the initial voltage applied to the pilot light, as no voltage drop is created across resistor 56 until there is plate current draw in the amplifying tubes. By the time this takes place the initially high heater current has dropped in value and the additional energizing effect resulting from plate current draw is the function of the combined resistance of the resistors 55 and 56, so that by choice of the value of the resistor 56 the pilot light can even be made to light up more brilliantly during normal operation of the apparatus than initially. If the amplifier tubes are biased so as to have low plate current draw the resistor 56 in this circuit might well have a value of about 15 ohms.

Figure 4 is a fragmentary portion of another pilot lamp energizing arrangement which makes pilot light energization a function of plate current draw. In this case only the filter section of a power supply system is shown, comprising the choke 60 and condensers 61 and 62. In the positive output lead from the filter, providing the B+ current for the amplifying tubes, is inserted a resistor 63, and the pilot light is placed in shunt with this. In this arrangement energization of the pilot light 64 is solely a function of plate current draw, and accordingly the value of resistor 63 must be somewhat higher than in connection with the arrangements previously described, where pilot light energization was a function of plate current draw and heater current draw combined. For the particular tubes and circuit illustrated in Figure 2, for example, and with a 6-8 volt .15 ampere pilot light, the resistor 63 might well have a value of about 100 ohms. While this form is not my preferred arrangement, as the pilot light does not become illuminated immediately upon turning on the switch, but only after there is plate current draw by the amplifying tubes, this arrangement is preferable to those now commonly used in that the pilot light is not subjected to over voltage initially.

It will be understood, of course, that any of the arrangements previously described may be used with equal advantage where the power pack arrangement is of the full wave rectifying type. Referring now more particularly to Figure 5, the A. C. supply wires 70 and 71 are shown as energizing the primary of a power transformer 72, the transformer in this case having a center-tapped secondary with its center grounded and its outer ends connected to the anodes of a full wave rectifying tube 73, which may be of tube type No. 25Z5, for example. Heater current for the rectifier tube and the amplifying tube is again provided by a direct connection to the A. C. lines or primary side of the transformer, as by the wires 74 and 75. The particular pilot light energizing arrangement illustrated in this case is similar to that shown and described in Figure 3, comprising resistors 76 and 77 in series with the primary of a transformer, the pilot light 78 being connected in shunt with these, and heater current being taken off from the center point between these resistors through an appropriate current limiting resistor 79.

While I have shown and described certain embodiments of my invention, it is to be understood that it is capable of many modifications. Changes, therefore, in the construction and arrangement may be made without departing from

the spirit and scope of the invention as disclosed in the appended claims.

I claim:

1. Electronic apparatus of the character described adapted to be connected to an alternating current power source, including: a tube having at least plate and cathode elements, a plate cathode circuit associated therewith and heating connections for the cathode element; a transformer having electrically separate primary and secondary windings; means for connecting the secondary winding into the plate cathode circuit of said tube; means for connecting the primary winding to said power source; and means for connecting said heating connections directly to said power source.
2. Electronic apparatus of the character described adapted to be connected to an alternating current power source, including: a plurality of amplifying tubes each having at least plate, grid and cathode elements and heating connections for the cathode element; a transformer having electrically separate primary and secondary windings; apparatus for supplying plate voltage for each of said tubes from the secondary winding; means for connecting the primary winding to said power source; and means for connecting the heating connections of all of said tubes directly to said power source.
3. Electronic apparatus of the character described adapted to be connected to an alternating current power source, including: a plurality of amplifying tubes each having at least plate, grid and cathode elements and heating connections for the cathode element; a rectifying tube having at least plate and cathode elements and a plate-cathode circuit associated therewith; a transformer having electrically separate primary and secondary windings; means for connecting the secondary winding into said plate-cathode circuit; means for supplying plate voltage for all of the amplifying tubes by a circuit connection from said rectifying tube; means for connecting the primary winding to said power source; and means for connecting the heating connections of all of said tubes directly to said power source.
4. Electronic apparatus of the character described adapted to be connected to an alternating current power source, including: a plurality of amplifying tubes each having at least plate, grid and cathode elements and heating connections for the cathode element; a rectifying tube having at least plate and cathode elements and a plate-cathode circuit associated therewith; a transformer having electrically separate primary and secondary windings; means for connecting the secondary winding into said plate-cathode circuit; means for supplying plate voltage for all of the amplifying tubes by a circuit connection from said rectifying tube; means for connecting the primary winding to said power source; and means for connecting the heating connections of all of the tubes having such connections directly to said power source.
5. Electronic apparatus of the character described adapted to be connected to an alternating current power source, including: a plurality of amplifying tubes each having at least plate, grid and cathode elements and heating connections for the cathode element; a transformer having electrically separate primary and secondary windings, said secondary winding having at least double the number of turns of the primary, the transformer being designed to handle the plate power requirements of said amplifying tubes but

being of insufficient capacity to also handle the filament power requirements thereof; a supply circuit for supplying plate voltage for each of said tubes from the secondary windings; means for connecting the primary winding to said power source; and means for connecting the heating connections of all of the tubes having such connections directly to said power source.

6. Electronic apparatus of the character described adapted to be connected to an alternating current power source, including: a plurality of amplifying tubes each having at least plate, grid and cathode elements and heating connections for the cathode element; a transformer having a primary winding and a secondary winding having at least double the number of turns of the primary, the transformer being designed to handle the plate power requirements of said amplifying tubes but being of insufficient capacity to also handle the filament power requirements thereof; means for supplying plate voltage for each of said tubes from the secondary winding; means for connecting the primary winding to said power source; and means for connecting the heating connections of all of the amplifying tubes directly to said power source, this means including a series resistor.

7. Electronic apparatus of the character described adapted to be connected to an alternating current power source, including: a plurality of amplifying tubes each having at least plate, grid and cathode elements and heating connections for the cathode element; a rectifying tube having at least plate and cathode elements, heating connections for the cathode element and a plate-cathode circuit associated therewith; a transformer having a primary winding and a secondary winding having at least double the number of turns of the primary, the transformer being designed to handle the plate power requirements of said amplifying tubes but being of insufficient capacity also to handle the filament power requirements thereof; means for connecting the secondary winding into said plate-cathode circuit; means for supplying plate voltage for all of the amplifying tubes by a circuit connection from said rectifying tube; means for connecting the primary winding to said power source; and means for connecting the heating connections of all of said tubes directly to said power source, this means including a series resistor.

8. Electronic apparatus of the character described, including: a tube having at least plate and cathode elements; apparatus providing a plate cathode circuit for said tube; a pilot lamp; a resistor connected in the path of all the space current passing through said tube and in the path of at least a portion of the current used for heating said cathode; and connections between said resistor and said pilot lamp for energizing the latter.

9. Electronic apparatus of the character described, including: a rectifying tube having at least plate and cathode elements; a pilot lamp; a circuit for supplying space current for said tube, this circuit including a resistor so connected as to have all of said space current passing therethrough; a circuit for supplying cathode heating current for at least said tube, this circuit

including said resistor and another resistor; and connections between resistance means and said pilot lamp for energizing the latter, this resistance means including said first mentioned resistor and at least one other resistor.

5 10. Electronic apparatus of the character described, including: a rectifying tube having at least plate and cathode elements; a pilot lamp; a circuit for supplying space current for said tube, this circuit including a resistor so connected as to have all of said space current passing therethrough; a circuit for supplying cathode heating current for at least said tube, this circuit including said resistor and another resistor directly in 15 series with the first mentioned resistor; and connections between said two series resistors and said pilot lamp for energizing the latter.

11. Electronic apparatus of the character described adapted to be connected to an alternating current power source, including: a plurality of amplifying tubes each having at least plate, grid and cathode elements and heating connections for the cathode element; a transformer having electrically separate primary and secondary windings; a supply circuit for supplying plate voltage for each of said tubes from the secondary winding; a circuit for connecting the primary winding to said power source, said circuit including a resistor; means for connecting the heating 20 connections of said tubes directly to said power source through said resistor; and a pilot lamp connected to said resistor.

12. Electronic apparatus of the character described adapted to be connected to an alternating current power source, including: a plurality of amplifying tubes each having at least plate, grid and cathode elements and heating connections for the cathode elements; a transformer having electrically separate primary and secondary windings, said secondary winding having at least double the number of turns of the primary, the transformer being designed to handle the plate power requirements of said amplifying tubes but being of insufficient capacity to also handle the filament power requirements thereof; a supply circuit for supplying plate voltage for each of said tubes from the secondary winding; a circuit for connecting the primary winding to said power source through a resistor; means for connecting the heating elements of all of the tubes having heating connections directly to said power source, one of these connections being through said resistor; and a pilot lamp connected to said resistor.
